UNITED STATES PATENT OFFICE.

JOHN C. YETTER, OF CHICAGO, ILLINOIS, ASSIGNOR TO THE TRIBUNE COMPANY, OF CHICAGO, ILLINOIS, A CORPORATION OF ILLINOIS.

METHOD OF AND PRESS FOR MULTICOLOR PRINTING IN INTAGLIO.

Application filed November 11, 1920. Serial No. 423,215.

To all whom it may concern:

Be it known that I, JOHN C. YETTER, a citizen of the United States, residing at Chicago, in the county of Cook and State 5 of Illinois, have invented new and useful Improvements in Methods of and Presses for Multicolor Printing in Intaglio, of which the following is a full, clear, and exact description.

10 My invention relates to intaglio printing and particularly to the art of and means for multi-color printing in intaglio.

In printing presses of this class every etched cylinder and impression cylinder, 15 possesses an individuality all its own; the metal of which the circumference of the etched cylinder is made; the depth of the etching on its surface; the diameter of the cylinder, and many other conditions enter 20 into their individual peculiarities, and these peculiarities affect the travel of the web of paper over the same, and the impressions made by them, and the impressions received by the paper vary according to the thickness 25 and quality of the paper; the consistency and color of the ink used in making the impression and the moisture imparted to the paper by the same.

Heretofore in printing multi-color work in 30 intaglio in which say, three colors were employed, it was customary to use one press and to print but one color at a time in said press. Cut sheets of paper were run through this press that had but one impression and one 35 etched cylinder, and these sheets, after they had dried were then run through the impression and etched cylinder of a second press, or the same press in which a new etched cylinder had been introduced and 40 then, after being dried a second time were run through cylinders of a third press, or, through the same press in which another etched cylinder had been inserted. If the same press was used for all three impressions it was necessary to re-adjust the 45 mechanism thereof for both the second and third color impressions so that the impression received by the paper from one cylinder would register with the color impression 50 received by the paper from the next cylinder. This required very careful adjustment and expert manipulation and it was seldom possible to print more than 1200 colored pictures an hour by the intaglio process as 55 heretofore practiced.

My invention has for its object the printing of colored work on a continuous web of paper that is continuously run through a press possessing a plurality of sets of intaglio printing cylinders, in such manner, 60 that the peculiarities of the cylinders and the differences in the quality and thickness of the paper, and other conditions that might affect the same, are perfectly controlled or compensated for, and perfect 65 registration of the impressions are effected in the several cylinder units of the press, to produce perfect and harmoniously colored work, at a speed comparable to that of an ordinary continuous web newspaper printing press. This I accomplish by the means 70 hereinafter fully described.

In the drawings:

Figure 1 is a side view of my improved intaglio multi-color printing press. 75

Figure 2 is a diagrammatical view of the same.

Figure 3 is a plan view of a broken away portion thereof embodying the adjustable speed friction gearing. 80

Figure 4 is a vertical section taken on line 4, 4, Figure 3, looking in the direction indicated by the arrows.

Figure 5 is a transverse section taken on line 5, 5, Figure 3 looking in the direction indicated by the arrows, and of mechanism disposed to the left of the same. 85

Figure 6 is a side view of a fragment of the press showing the adjustable guide-roller mechanism. 90

Figure 7 is a plan view thereof.

Figure 8 is a transverse section of a detached portion of the press showing the mechanism for adjusting the pressure of the impression cylinder. 95

Figure 9 is a side view of a detached portion of said machine illustrating the feed controlling mechanism.

Figure 10 is a transverse section thereof taken on line 10, 10, Figure 9, looking in 100 the direction indicated by the arrows.

Figure 11 is a side view of a broken away portion of the press embodying the mechanism for simultaneously adjusting the pressure of the impression cylinders. 105

Figure 12 is a plan view of one of the detached gearing units shown in Figure 11.

Figure 13 is a plan view of the means employed to dry the paper separated from the press. 110

Figure 14 is a plan view of one of the adjustable supports for the bearings of the impression-cylinder shown in Figure 8.

The continuous web of paper E which is fed through the press is taken from a transverse roll 9 whose removable shaft is journaled in upright endframes of a truck 10, that is capable of travelling laterally in front of the press, and from the latter the 10 web passes over a guide-roller 11, then under a spring depressed idler-roller 12 and then up over a second guide-roller 13. The feed of web E from roll 9 is regulated by one or more parallel endless belts 14, which pass 15 around pulleys 15 and 16 and have their lower stretches bearing upon the top of the roll. Pulleys 15 and 16 are mounted on shafts 16' and 17, respectively, and shaft 16' has its ends journaled in the free ends of 20 corresponding links 18. The inner ends of links 18 are loosely mounted on shaft 17, and the latter has its ends journaled in the side-frames 19 of the press. Shaft 17 derives motion through the medium of a gear 25 21 thereon, an intermeshing idle gear 20 (both of which are shown only in dotted lines in Figure 1 of the drawings), and a gear 22 that derives motion indirectly through the medium of a vertical shaft 127 30 from the main shaft F and travels at the same speed as the latter.

From the guide-roller 13, the web of paper travels under and around a fixed guide-roller 24, journaled in brackets projecting 35 rearwardly from side-frames 19 thence the web, moves vertically upward to and over a guide-roller 25 and it then travels down under and around a similar guide-roller 26. From this last guide-roller, 26, the web runs 40 to and around a feed-controlling roller 27 for about 240 degrees of its circumference, and then continues on its way to the first intaglio printing cylinder of the first printing unit, A, as will hereinafter more fully 45 appear.

Feed control roller 27, shown more in detail in Figs. 9 and 10, is mounted on a transverse shaft 28 and the latter is journaled in bridges 19^a that connect the side-frames 19, 50 of the unit D, through which the web first passes with the side-frames of the next unit A, in which latter the web receives its first impression as will hereinafter more fully appear. One end of shaft 28 extends 55 beyond its bearing and is provided with a gear 29. Near its opposite bearing this shaft has a gear 30 thereon, that engages a pinion 31 which is mounted upon a transverse shaft 32, whose ends are journaled in blocks 33, 60 that are vertically slidable between the uprights 34, 34, of standards 35 supported upon and secured by screws or otherwise to the bridge 19^a. The blocks 33 are maintained pressing downward through the 65 medium of springs 37, surrounding headless

gage-screws 38, which latter are tapped through a cap 39 connecting the upper ends of jaws, 34, 34, of the standards 35. The upper end of each gage-screw 38 has lock-nuts 40 thereon by means of which, when 70 said gage-screws are properly adjusted to limit the downward movement of the bearing-blocks 33, sufficiently to produce the desired downward pressure of a roller 41 (mounted upon shaft 32) upon the feed-controlling roller 27, it can be locked and 75 positively maintained in its adjusted position.

In order to raise the roller 41 from the feed-roller 27, say, when it is desired to thread the web of paper E between the same, 80 I have provided shaft 32 next the inside of its bearings with channeled bosses 42, (shown in dotted lines in Figure 10 of the drawings), and have provided a rock-shaft 44 the ends of which are journaled in lugs 85 45, made integral with and arising from bridge 19^a. This rock-shaft has arms 46, 46, the upper edges of the rear ends of which are concaved and engage the channeled portions of bosses 42. One end of rock-shaft 44 90 extends through its bearings and has the boss of a depending arm 47 secured thereon. The lower end of this arm 47 terminates in a suitable hand-grasp and on the arm 47 between this hand-grasp and rock-shaft 44, 95 is provided an integral housing in which a transverse bolt 48 is seated, which, when said arm 47 is in the position shown in Figures 9 and 10 of the drawings, is shot by the pressure of a coil-spring 49 surrounding it into 100 a suitable depressed seat in cross-frame 19^a and holds the rock-shaft and arms 46 in the position shown in the drawings. When it is desired to raise the pressure-roller 41 out of contact with feed-roller 27, arm 47 is grasped 105 and moved so as to release bolt 48 from its depression in cross-frame 19^a and thus raise arms 46 and blocks 33.

Shaft 28 of the feed-roller is driven through the medium of the gear 29 by a 110 pinion connected to and revolvable with a friction-wheel 50. The construction and operation of this friction-wheel, 50, and the driving mechanism for regulating the speed thereof is the same as that hereinafter fully 115 described in relation to the registering rollers, that are interposed between the printing cylinders of the first printing unit and the second, the second printing unit and the third; and the third printing unit and the 120 fourth.

It will be noticed that the feed roller 27 is a tension roller and absolutely controls the supply of paper to the first printing unit. Thus the web of paper from the feed-roller 27 travels downward to a guide-roller 51, thence runs to and between the etched printing cylinder 7, and the impression cylinder 6 of the first printing unit A. The etched cylinders of my improved print- 125 130

ing press are constructed similar to that of the intaglio printing presses now in use, and their copper circumferences have the lines, indentations and the interstices, scratched and otherwise made therein to produce the first impression which it is intended to make upon the web of paper passing between them and their coacting superposed impression-cylinder. These scratches, indentations and 10 interstices of the etched cylinder of each unit are filled with ink from a suitable fountain 52 containing the first color it is desired to print, and the superfluous ink is scraped by a suitable knife or doctor 53 engaging 15 the surfaces of the same, as heretofore. The construction of this fountain and knife, however, and the means and devices used in connection therewith are old and constitute no part of my invention and the description thereof is therefore omitted. These 20 etched cylinders are driven through the medium of suitable gearing by a vertical shaft 23, but as this gearing is old in the art a description thereof is deemed unnecessary. 25 In order that the proper impressions may be made upon the web of paper the superposed impression cylinder 6 of each unit is made vertically adjustable. The circumference of this impression roller is made of 30 hard rubber and the suction which is exerted by this rubber upon the ink filled scratches, indentations and interstices of the etched surface of the etched cylinder 7, depends upon the "flat," as it is commonly 35 called, made in the contacting surface of the impression roller according to the pressure of the same against said etched cylinder. The reduced ends of the impression cylinder terminate in and are secured to 40 suitable ball-bearing disks 54, which latter are journaled in hangers 55, secured to and depending from the lower squared end of a vertical rod 56. The portion of this rod immediately above 45 its lower squared end is exteriorly threaded and engages the threaded interior of a bushing 57, and above this bushing rod 56 is square in cross-section and extends axially through an adjustable screw 58. Screw 58 has its lower portion cored centrally and the diameter of the bore thus produced is such that the bushing 57 just fits into it. Above this bushing, rod 56 is, within the 50 cored out portion of screw 58, surrounded by a coil expansion-spring 59 and by turning the bushing said spring is compressed so as to produce just the proper downward pressure of the impression cylinder 6 upon the etched cylinder 7. Screw 58 has its 55 lower exteriorly smooth portion seated in a bracket 60, that projects inwardly from the side-frames 19 of the press. The portion of the screw 58 above the enlarged upper flat end of this bracket is exteriorly 60 screw-threaded and is engaged by a circular nut 61, whose outer circumference is provided with a worm gear 62. This nut 61 is interposed between said bracket and a plate 63, which latter is spaced from the bracket by tubular legs 64, 64, and is secured to 65 said bracket by means of bolts 65, 65, extending through said legs. The upper end of screw 58 extends through a smooth opening in plate 63 and has a gage-nut 66 70 screwed on its upper projecting end. The upper screw-threaded end of rod 56 extends up above screw 58 and has lock-nuts 67 thereon. By loosening gage-nut 66, the screw 58, can be moved vertically 75 up or down by turning nut 61, and by loosening nuts 67, the rod 56 can be moved up or down to obtain just the right pressure of the impression cylinder on the etched cylinder to get the "flat" necessary to make the right impression on the paper. 80 The lower ends of the brackets, 60, are provided with lugs 68 that project in the direction of the length of the side-frames and toward the rear of the press and these lugs have pendent links 69 pivoted there-in that have transverse slack-rollers 70 journaled in their lower ends. The web of paper after it passes between the etched cylinder and the impression cylinder of the first unit A passes under said slack-roller, 70, and 85 then vertically upwards to and around about three-quarters of the circumference of a hollow heated revolving drum 71 the portion of the circumference of which, with which the web of paper comes in contact, being 90 enclosed within a heat-chamber 72 whose intake 73 derives a heated current of air from a longitudinally disposed pipe 74. 95 The gear 29 on that end of shaft 28 that extends through its bearings is engaged and 100 driven by a pinion 76, that is made integral with the boss of the large friction disk 50 hereinafter referred to which disk is loosely mounted and adjustable longitudinally upon a spindle, 78, but the means for accomplishing this result, which are illustrated in Figures 3 and 4 of the drawings do not constitute part of the subject-matter of the invention embodied in my improved multi-color intaglio press and, therefore, are not specifically described herein. The disk 50 is placed 110 between and driven by small friction disks 79 and 80, respectively. 115 Disk 79 is mounted on a hollow spindle 81, shown in dotted lines in Figure 3 of the drawings, and this spindle 81 is mounted on a longitudinal shaft 82 and is adapted to revolve therewith but be movable longitudinally thereon. The spindle 81 is parallel to and revolves the spindle on which disk 80 is mounted, through the medium of corresponding gears 83 and 84, and both of these spindles are journaled in the same block 85, which latter is loosely mounted and movable laterally on a carrier 86, through the me- 120 125 130

dium of a dovetail groove and a tenon 87 engaging the same. The block 85 is adjusted laterally on carrier 86 by a transverse adjusting screw 88, and the carrier is adjustable longitudinally by means of an adjusting screw 89. Screw 88 extends through a smooth bore in the tenon 87 and engages a lug 75 projecting down from block 85, as shown in dotted lines in Figure 4 of the drawings, and the screw 89 extends through the smooth bore of a transverse ridge of a bracket 90, upon which it is mounted, and its threaded portion engages a lug α , depending from carrier 86, which bracket, 90, is secured to and projects from the side-frame of the press.

The heating drum 71 has journals that have suitable bearings in the side-frames of each of the units, preferably in the same vertical transverse plane as the bearings of the etched and impression cylinders thereof and one of these journals extends through its bearings and has a gear 91 securely mounted thereon, which latter in unit A, derives motion from an idle pinion 92, mounted on one of the sideframes, which pinion is driven by a gear 93, fast on the end of a boss carried by a friction disk 94, which latter is also journaled in the sideframe. In units B and C the drum 71 is driven through the medium of pinions 91' fast on the shafts of the friction disks 94 in mesh with the gears 91, the friction disks 94 all being in direct contact with smaller friction disks or rollers 95. The friction disks 95, are mounted, adjusted and driven through the medium of shaft 82, hereinbefore referred to, and by adjusting these small friction disks, toward or from the axes of the large friction disks 94 the speed of the latter and the mechanism connected therewith can be increased or decreased according to the speed it is desired the web of paper should have as it passes between the etched cylinder 7 and the impression roller of the first unit, and travels around the heating drum thereof. The construction and operation of the friction devices just described are substantially the same as those shown in Figures 3 and 4 of the drawings, and hereinbefore described, and therefore, a more detailed drawing of the same, than that illustrated in Figure 1, is deemed unnecessary.

From the heating-drum 71 the web of paper passes around a guide-roller 96, thence toward the front of the press to and around a guide-roller 97 that is journaled in the same bracket 98 in which guide-roller 51 is journaled and from the latter vertically up and over a guide-roller 99. From the latter the web pursues its course rearwardly and upwardly over a guide-roller 100 and then downwardly and around a registration cylinder 101 and then upwardly again to and over another guide-roller 102 and then ver-

tically downwards to and over the roller 51 of the second printing unit B.

This registration-cylinder 101 is securely mounted on a transverse shaft 103, that is journaled in the side-frames of the press and has one of its ends extend through its bearings and provided with a gear 104, as shown in dotted lines in Figure 5 of the drawings. The gear 104 is driven by a gear 105 also shown in dotted lines in said figure, and the latter is secured concentrically to and made integral with the boss of a large friction disk 106. The friction disk 106, is engaged by smaller friction disks mounted on a spindle 107, and on a longitudinally disposed shaft 108, respectively, which are connected by corresponding gears 109 and 110. The axes of these shafts and the friction gears are at right angles to the axis of the large friction gear 106, and the construction of the mechanism in which the small disks are mounted and the means for adjusting the same towards and from the center or rotation of said large disk, are the same as that of disk 50 and disk 79 and 80 hereinbefore described, and can be manipulated in the same manner thereas to enable the speed of the registration cylinder to be controlled to a nicety.

The construction and operation of the mechanism for guiding the continuous web of paper therethrough, for printing the second color thereon and for regulating the speed of said web, is identically the same in the second printing unit B and third unit C, as in the first units it may be deemed advisable to add to the press, with the exception of the last unit.

After the web of paper leaves the guide-rollers 97 of the unit C, it moves vertically upwards to and over a guide-roller 112, and then continues forward over corresponding guide-rollers 113 and 114, in a horizontal plane above the registration cylinders, to a point approximately over the friction-disk 50 that actuates the supply-roller 27. From this last mentioned guide-roller the web continues downwards to and around another guide-roller 115, and then up to and around a registration cylinder 116. The web passes under this registration cylinder, which it engages before reaching printing cylinders of the last unit D, but passes over the latter and then continues downwards to and under a guide-roller 117 and from thence passes on its way to and between the etched cylinder 119 and the impression cylinder 118 of said last unit D, which prints a single impression on the side of the web of paper opposite that on which several colors had previously been printed.

After it receives its impression between the etched and impression cylinders of this last unit, the web extends directly to and around a heating-drum 120 and from thence

continues around and past guide-rollers 121 and 122 and over a cylinder 123, whose function is that of a tension roller to keep the web taut, as it leaves the drum 120, and 5 to discharge the same to the folding mechanism or delivery apparatus of the press. The cylinders 118, and 119 are constructed, actuated and adjusted in the same manner as cylinders 6 and 7, hereinbefore described, 10 but, if desired it is obvious a type cylinder can be substituted for the etched cylinder 119. The heating-drum of the last unit is rotated through the medium of an idle friction gear 124, and a larger friction disk 125, 15 and the latter is driven by means of small disks by a shaft 126, alining with shaft 82, which, together therewith is revolved by bevelled gear connections 153' with a vertical shaft 127, the lower end of which 20 latter is connected to and driven through bevelled gears 151', by the drive-shaft F.

Each of the registration-cylinders 101 and 116 is engaged by a friction wheel 128 to assist in keeping the web in contact therewith as it passes around the same. The 25 wheels 128, 128, that engage the cylinders 101, are loosely journaled on studs 129 projecting laterally from the adjacent ends of arms 130, which latter are loosely mounted 30 on and project radially from a transverse rock-shaft 133. Complementary arms 132 are secured to and project from this rock-shaft along-side of arms 130, and are provided with offset outer ends. Bars 131 are 35 extended through these offset ends and have their outer ends tapped into the ends of arms 130, nearest the registration cylinder 101, and between the outer offset end of arm 132 and the outer ends of arms 130 40 carrying wheel 128, bars 131 are surrounded by coil springs 135, that yieldingly press wheels 128 against cylinder 101. One end of said rock-shaft 133 extends through its 45 bearings in the side-frame 19 of the press, and has an arm 134 projecting therefrom that terminates in a suitable handle, and between this handle and its boss it is constructed with a transversely elongated segmental slot 135, through which a set-screw 50 136 passes, whose inner end is tapped into the adjacent side-frame 19. By loosening screw 136 the arm 134, and rock-shaft 133 can be adjusted on their common axes to obtain the desired tension of springs 131 55 and consequent pressure of wheels 128 against cylinder 101, and by tightening said set-screw this adjustment and pressure can be maintained.

In Figures 8, 11 and 12, mechanism is 60 disclosed for actuating the means that can be operated to simultaneously adjust the impression cylinders. This adjustment is principally accomplished by turning the nut 61, and this is done by a worm 140, securely 65 mounted on a transverse shaft 141, journaled

in suitable bearings in the side-frames of the press. The ends of these shafts 141 extend through their bearings, and at one end they have a hand-wheel 142, secured thereto by means of which they can be revolved, and 70 as shown in Figure 8 of the drawings, when said shaft is turned it simultaneously adjusts the hangers 55 in which the impression cylinder is journaled up or down to a corresponding extent to obtain just the 75 "flat" desired.

If desired the impression cylinder of each printing unit may be adjusted independently of the impression-cylinders of the other units, and, in this event, the end of shaft 141 opposite to that on which is wheel 142, may terminate in its bearings. I prefer, however, to securely mount on this last mentioned extended end, a sleeve 143, whose end farthest from the side-frame of the press is flanged 80 circumferentially to provide a circular clamping head 144. The outer face of this head has a concentric groove 145 therein that is substantially T-shaped in cross-section and the circumferentially flanged end 85 146 of the adjacent end of the boss of a worm-gear 147 is clamped to head 144 and is adjusted concentrically with reference thereto by means of a bolt 148 the head of which is situated in the inner wider portion 90 of the T-shaped groove 145, and the barrel of which extends out through a suitable opening in the said flanged end 146 of the boss of the worm-gear 147, and has a nut 149 on the outer screw-threaded end thereof 95 with which to clamp the head 144 and end 146 together. The worm-gear 147 is loosely mounted on the end of shaft 141, and is secured thereto by means of a set-screw 150, and said gear, 147, is engaged by a worm 100 151 securely mounted on a longitudinal shaft 152. By loosening the clamping head 144 from the flanged end 146 of the boss of worm-gear 147, and loosening the set-screw 150, the compression cylinder 6 of each unit can 105 be adjusted with reference to its co-acting etched cylinder independently of those of the other printing units, and when such adjustment has been satisfactorily accomplished in each unit the clamping-heads 144 110 and the flanged ends of the worm-gears 147, are clamped together, and said gears secured to shafts 141 by tightening nuts 150, and turning shaft 152 simultaneously and correspondingly adjusts the impression cylinders 115 120 of all units.

As hereinbefore stated the means for adjusting the compression-cylinder of the last printing unit of the press is the same as that hereinbefore described. The same is true 125 of the means for operating the adjusting mechanism thereof, except that the longitudinal shaft 152 on which its worms 151 are mounted does not aline with shaft 153, and is therefore connected to the same and is 130

actuated thereby through the medium of sprockets 154 and 155 mounted on said shafts, respectively and a chain 156 substantially as shown in Figure 11 of the drawings.

5 The upper end of shaft 127 is connected by bevelled gear 160 to a longitudinal idle-shaft 161, and at the end of idle-shaft 161 opposite said bevelled gears it is connected to and drives shaft 108 through the medium of gears 162, shown in dotted lines in Figure 1 of the drawings.

The registration rollers 116, of printing unit D, as well as registration rollers 101, are actuated by shaft 108, through the medium 15 of friction gearing 163 and 164, which latter, and adjusting devices therefore are the same as that illustrated in Figures 4 and 5, of the drawings, and the pressure-roller 165 used in connection with said registration roller 116, 20 and means 166 used in connection with the same are replicas of arms 130 and 132 and rod 131, only arranged upside down. The illustration of these pressure devices shown in Figure 1 of the drawings are therefore 25 considered sufficient. The discharge roller 123 is substantially the same in construction and operation as the registration rollers, and it derives motion through a train of adjustable friction gears 167 and is engaged by pressure mechanism 168 the construction of 30 which is the same as that used in conjunction with said registration rollers.

In view of the fact, therefore, that all of 35 the mechanism for actuating the etched or printing cylinders, of the several printing units of my improved press, and the means for adjustably controlling the speed of the continuous web of paper through the same are driven from one source, namely, the 40 drive-shaft F, the delicate adjustment particularly of the web controlling mechanism, insures a perfect registration of the said web with the printing cylinders and the impressions derived from the same, so that the 45 correct and harmoniously colored design or picture can be obtained, without the usual delays now encountered due to the withdrawal of the paper from the press, the drying 50 of the paper, the introduction of new etched cylinders, the adjustment of the impression-cylinder to get the desired "flat" and adjustment of the feed to register the paper for each impression, particularly after the first.

55 While the invention has been disclosed in connection with multi-color printing in intaglio, it is to be understood that the invention is not limited thereto but is applicable to printing presses and processes capable of 60 printing impressions of a single color or composite impressions of either a single color or where there are used shades and tints, and whether using etched, engraved cylinders or cylinders with raised, cameo printing surfaces or type.

What I claim as new is:

1. A method of multi-color printing in intaglio consisting of continuously moving a continuous web of paper successively between several co-acting sets of etched cylinders and their respective impression cylinders, adjustably controlling the speed of the supply of said web, each of said sets being limited to print only a part of the finished design, and manipulating said web while it is passing from one set to the set next following the same to cause the impression made by the last mentioned set to coincide in relative position to the points and features of the first mentioned set. 70

2. The method of multi-color printing in intaglio consisting of continuously moving a continuous web of paper successively between several coacting sets of etched cylinders and their respective impression cylinders, adjustably controlling the speed of the supply of said web, each of said sets being limited to print only a part of the finished design, adjustably controlling the speed of the web after it leaves the last of said sets to manipulate said web both before, after and between each pair of said sets to cause the impression made by one set to coincide in relative position to the points and features of the set next preceding the same. 80

3. The method of multi-color printing in intaglio consisting of continuously moving a continuous web of paper successively between several coacting sets of etched cylinders and their respective impression cylinders, adjustably controlling the speed of the supply of said web, printing only a part of the finished design in each of said sets, and frictionally manipulating said web between each pair of sets to cause the impression made by the last of said pair of sets to coincide in relative position to the points and features of the impression made by the first mentioned set. 100

4. The method of multi-color printing in intaglio consisting of continuously moving a continuous web of paper successively between several coacting sets of etched cylinders and their respective impression cylinders, adjustably controlling the speed of the supply of said web, printing only a part of the finished design in each of said sets, heating said web between said sets, and frictionally manipulating said web between each pair of sets to cause the impression made by the last mentioned press to coincide in relative position to the points and features of the impression made by the first mentioned set. 105

5. A multi-color intaglio printing press comprising a tension roll for adjustably controlling the speed of the web of paper from the supply roll to the first printing unit, a plurality of printing units each adapted to print in a different color, guide rolls for con- 125

veying a continuous web of paper there-through, a registration cylinder the speed of which is adjustable and arranged between each pair of units, and tension rollers for 5 keeping the paper taut.

6. A multi-impression printing press comprising a series of printing units, means for continuously feeding a web through the press, said means including means for controlling the speed of travel of the web to the units, each controlling means comprising a roll engaging the web, and friction means for driving the roll, each friction means having driving and driven friction members, and 10 means for varying the relation of said members whereby the roll will effect increased or decreased feeding stress upon the web while being continuously fed through the press to correct for registration of the impressions 15 made by the units upon the web.

7. A multi-impression printing press, comprising a series of printing units, means for continuously feeding a web through said units serially, said means including a control 20 roll for each of said units and engaging the web entering said unit, means for driving each roll and including adjustable frictional driving and driven members, means for adjusting the relation of said members for increasing or decreasing the speed controlling 25 effect of the roll upon the web entering said unit for causing succeeding impressions to register with previously impressed impressions.

30 8. A multi-impression printing press, comprising a series of printing units, means for continuously feeding a web through said units serially, said means including a control roll for each of said units and engaging the web entering said unit, friction gearing for driving each roll and including a driven disc connected to the roll and a driving disc frictionally engaging the driven disc, means for adjusting the relation of the driving disc 35 to the driven disc to effect variations of speed thereof and the roll for accelerating or retarding the normal speed of the web while being continuously fed through the units.

40 9. A multi-color printing press consisting 50 of several printing units each comprising a printing cylinder and an impression cylinder, a roller from which a continuous web of paper is fed to and between said printing and impression cylinders of each unit, a drying apparatus for said web after it leaves said cylinders, and frictional means between the drying apparatus of one unit and said cylinders of the next unit for increasing or decreasing the speed of said web.

45 10. A multi-color printing press consisting 55 of several printing units each comprising a printing cylinder an impression cylinder and a drying apparatus, a roller from which a continuous web of paper is fed to 60 and between the said cylinders of each unit,

and a friction roller between the drying apparatus of one unit and the cylinders of the next unit, and means for increasing or decreasing the speed of the periphery of said roller and correspondingly altering the 65 speed of the web of paper fed to the last mentioned cylinders.

70 11. A multi-color printing press consisting 75 of several printing units each comprising a printing cylinder an impression cylinder and a drying apparatus, a roller from which a continuous web of paper is fed to and between the said cylinders of each unit, and a friction roller between the drying apparatus of one unit and the cylinders of the 80 next unit over which said web passes, and means for increasing or decreasing the speed of said roller.

85 12. A multi-color printing press consisting 90 of several printing units each comprising a printing cylinder, an impression cylinder and a drying apparatus, a roller from which a continuous web of paper is fed to and between the said cylinders of each unit, and a friction roller between the drying apparatus of one unit and the cylinders of the 95 next unit over which said web passes, and adjustable friction gearing for increasing or decreasing the speed of said roller.

100 13. A multi-impression printing press, comprising a series of printing units, means for continuously feeding a web through said units serially, said means including a control roll for each of said units and engaging the web entering said unit, a supply roll, means for feeding the web from the supply roll to the feeding means, a driving mechanism for each control roll for normally feeding the web continuously through the units and comprising mutually engageable friction members, and means for varying the relation of the friction members for increasing or decreasing the normal speed of the control roll for hastening or retarding the web feed 105 into the respective unit.

110 14. A multi-impression printing press, comprising a series of printing units, means for continuously feeding a web through said units serially said means including a control roll for each of said units and engaging the web entering said unit, a supply roll, means for feeding the web from the supply roll to a control roll and including a friction driving device for said supply roll and normally acting to continuously feed the web to a control roll and a driving mechanism for each control roll for normally feeding the web continuously through the units and comprising mutually engageable friction members, and means for varying the relation of the friction member for increasing or decreasing the normal speed of the control roll for hastening or retarding the web feed into the respective units.

115 15. A multi-color printing press comprising 120

ing several printing units each comprising a printing cylinder and an impression cylinder, a roller from which a continuous web of paper is fed to and between the cylinders of each unit, means for varying the speed of said roller independently of said units, a drying and a registering unit between each pair of said printing units and over which the drying portions of said web are carried, 5 means for independently varying the speed of each drying portion passing said registering and printing units, and means for relatively independently varying the speed of said registering units relative to said drying and printing units.

16. A multi-impression printing press comprising a web supply device having means for feeding the web continuously to a tension device, a series of printing couples, a 10 tension device for receiving the web from the supply device and continuously feeding the web to the first couple of the series, registration devices for each succeeding couple and for continuously feeding the web from a 15 previous to a succeeding couple, friction drives for each of said devices, and means in each of said drives for varying the driving speed thereof independently of each other for increasing or decreasing the feed of the 20 web entering any of the couples or the tension device and during the continuous feed of the web.

17. A multi-color printing press consisting of several printing units each comprising a printing cylinder and an impression cylinder, a roller from which a continuous web of paper is fed to and between said printing and impression cylinders of said units, a tension roller for controlling the 25 speed of said web to the first of said units, a drying apparatus for said web after it leaves said cylinders and frictional means between the drying apparatus of one unit and said cylinders of the next unit for increasing or decreasing the speed of said web.

18. A multi-color printing press consisting of several printing units each comprising a printing cylinder and an impression cylinder, a roller from which a continuous 30 web of paper is fed to and between said printing and impression cylinders of said units, a tension roller for controlling the speed of said web to the first of said units, a drying apparatus for said web after it leaves said printing unit, frictional means between the drying apparatus of one unit and the cylinders of the next unit, for increasing or decreasing the speed of said web, and a tension roller for keeping the 35 web taut after it leaves the last unit.

19. A multi-color printing press consisting of several printing units each comprising a printing and impression cylinder, a drying apparatus, a roller from which a continuous web of paper is fed to and between the cylinders of each unit, a tension roller that controls the speed of said web from said roller to the first of said units, a friction roller between the drying apparatus of one unit and the cylinders of the next 45 unit, and means for increasing or decreasing the speed of the periphery of said friction rollers and correspondingly altering the speed of the web of paper fed to the cylinders of the next printing unit.

20. A multi-color printing press consisting of several printing units each comprising a printing and impression cylinder, a drying apparatus, a supply roller from which a continuous web of paper is fed to and between said cylinders of each unit, a tension roller that controls the speed of said web from said supply roller to the first of said units, a friction roller between the drying apparatus of one unit and the cylinders of the next 50 unit, means for increasing or decreasing the speed of the periphery of said friction rollers and correspondingly altering the speed of the web of paper fed to said printing units, and a tension roller 55 for keeping the said web taut after it leaves the last unit.

21. In a printing press comprising printing units each including printing and impression cylinders, means for feeding a continuous web to and between the cylinders of each unit, said means including cooperating friction driving and driven members, and means for adjusting the relation of said members during the feeding operation of the feeding means whereby the speed of the web may be increased or decreased as it moves to said cylinders for correct registry of the impression made on the web.

22. In a printing press comprising printing units, each including a printing and an impression cylinder, a supply roller from which a continuous web of paper is fed to and between said printing and impression cylinders, frictionally driven means between said units for increasing or decreasing the speed of said web independently of the speed of the cylinders of said units, said means including mutually engageable friction members, and means for varying the relation of said members for effecting variations in the driving speed thereof.

In witness whereof I have hereunto set my hand this 18th day of October, 1920.

JOHN C. YETTER.
